UNITED STATES PATENT OFFICE

STUART PARMELEE MILLER, OF TENAFLY, NEW JERSEY, ASSIGNOR TO THE BARRETT COMPANY, OF NEW YORK, N. Y., A CORPORATION OF NEW JERSEY

DISTILLATION OF TAR

Application filed February 5, 1927. Serial No. 166,082.

This invention relates to improvements in the distillation of tars and the production of pitches and distillate oils therefrom and includes a new method of tar distillation and 5 of pitch production. More particularly the invention relates to the recovery of desirable products from coal carbonization and gasification plants such, for example, as by-product coke ovens, illuminating gas retorts, etc. 10 The invention will be described more particularly in connection with the operation of by-product coke ovens.

In the ordinary operation of by-product coke ovens the gases produced by the coking 15 operation pass from the individual ovens through uptake pipes and goose-necks to a collector main common to a battery of ovens. The coke-oven gases leaving the ovens at high temperature are cooled in the collector 20 main and in condensers connected therewith to separate tar constituents therefrom. In many cases the gases are also substantially cooled in the goose-necks by sprays of ammonia liquor. The separated coal tar is 25 commonly shipped or conveyed to tar distillation plants where it is subjected to distillation to produce pitches and various other products.

Owing to the high temperature of the gases 30 from the coke ovens, and particularly because of the enormous amount of heat carried thereby, the successful operation of the collector main in connection with these ovens has always been a serious problem. The heat 35 carried by the gases, which leave the ovens at a temperature of approximately 700° C. or higher, is from twenty to thirty-five times that required for the distillation of all of the tar contained in the gases. A certain 40 amount of heavy tar or pitch separates in the collector main and such tar or pitch is subjected to the distilling effect of the gases at high temperature with the resulting formation in the main of solid hard pitch which 45 can in some cases be removed only by shutting down the plant and scraping or digging it out. It is customary to flush the main with a mixture of tar and ammonia liquor or with ammonia liquor alone, but this practice does 50 not always avoid the difficulty. In fact, the

use of water or ammonia liquor aggravates the situation in some cases because the pitches formed in the main are insoluble in water or ammonia liquor and hence are not flushed out unless an extremely large amount of the liquor is employed. 55

The use of a large quantity of ammonia liquor for flushing the collector main introduces a new difficulty because of the resulting lowered temperature of the gases. Thus, 60 by spraying ammonia liquor into the collector main in sufficient quantity to prevent accumulations of pitch therein, the temperature of the gases may be so reduced that a considerable proportion of the valuable oil 65 constituents which are present in the gases are condensed and are thrown down with the tar and can be recovered therefrom only by subsequent distillation.

It is the object of the present invention to 70 provide an improved process of tar distillation directly at the coal carbonization plant such as a by-product coke-oven plant, and especially an improvement in the operation 75 of the collector main or mains in connection with the by-product coke-oven plant whereby advantage can be taken of the heat carried by the coke-oven gases to distill the tar and separate volatile products therefrom so that 80 the latter can be recovered independently of the pitch which then constitutes a separate product of the operation. 85

According to the present invention the hot coke-oven gases as they come from the coke 90 ovens are utilized for the distillation of tar and the separation of vaporizable oils therefrom by bringing the tar into intimate contact with the hot coke-oven gases in the collector main while the gases are at a temperature high enough to accomplish the desired 95 distillation; and pitching of the main is prevented by flushing the main with a large amount of hot tar or pitch in excess of that distilled by the hot gases. The large excess of tar or pitch circulated through the main 100 is continually or intermittently drawn off as pitch and can be in part recirculated through the main with additional tar or pitch to be distilled, or it can be drawn off as a finished product or further distilled by 105

a separate operation. Where a plurality of short collector mains are employed, as hereinafter described, the tar or pitch may be passed in succession through several of the mains to effect progressive distillation thereof. Pitches having varying qualities and different characteristics, depending upon the regulation of the distillation operation, may be obtained.

10 The intimate contact of the tar with the hot coke-oven gases results in partial cooling of these gases from the temperature at which they normally escape from the coke oven, e. g., around 600 to 700° C. or in some 15 cases much higher. The temperature of these gases is sufficiently high and the volume of non-condensable gases is so great that the effective distillation of the tar can be accomplished in the manner indicated. The 20 amount of tar supplied and the intimacy and time of contact of the particles of the tar with the gases and, therefore, the nature and amount of oil distilled therefrom, can be varied. Effective distillation can be accomplished with a temperature drop of the gases 25 while passing through the collector main of, for example, 100° C., although with increased amount of tar or increased intimacy and time of contact a greater drop in temperature and increased distillation of oil can be attained.

30 The tar in turn will be heated by the hot gases and its temperature may be very considerably raised. Part of the heat, however, 35 is employed in vaporizing liquid constituents of the tar without corresponding increase in the temperature thereof so that the maximum temperature of the tar and of the resulting pitch may in some cases be considerably 40 below that of the gases. In order to avoid pitching of the main it is important that the tar used to flush the main and that circulating through the main be kept hot so that it is thinly fluid and so that any pitch 45 formed will be dissolved and blended therein. So long as the pitch is kept sufficiently hot it is thinly fluid and by omitting the cooling effect of excessively large amounts of ammonia liquor this thinly fluid condition of the tar can be maintained.

50 The distillation of tar in the collector main may be accomplished in a variety of ways involving the intimate contact of the tar with the gases therein. Preferably the introduction of ammonia liquor to the collector main is avoided except as hereinafter described and in place thereof the main is flushed with a sufficient quantity of tar or oil or tar and oil to ensure against any accumulation of 55 heavy pitch in the main. This object is readily accomplished if a sufficient quantity of the flushing medium is provided and if the temperature is kept high because the heavy pitch, if it is formed, is soluble in the hot tar or oil used and any accumulation will be dis-

solved and carried along with the stream of hot tar which flows through the main. The tar or oil or mixtures thereof can be circulated through the main, being introduced at one end thereof and withdrawn at the other, 70 or at intermediate points. It is important, however, to observe two important requirements; the first of which is that there should be an intimate mingling of the tar with the gases from the ovens at a high temperature 75 to effect the desired distillation, and the other that the surfaces of the main should be constantly washed with a large excess of hot tar or oil or mixtures thereof to prevent the accumulation thereon of heavy pitch. Both 80 of these purposes can be accomplished by the provision of suitable mechanical agitating devices within the main and actuated to maintain a constant and violent agitation of the tar as it flows through the main so 85 that the tar is splashed or thrown into the stream of coke-oven gases and onto the exposed surfaces of the main, either without or with the use of spray nozzles, etc., for spraying tar directly on to the surfaces of the 90 main.

95 The required agitation can be accomplished by the use of a rotating shaft running lengthwise of the main or a number of such shafts running across the main with suitable paddles thereon or by vertical shafts with similar paddles. Rotating cones or other agitating and splashing devices may be disposed in the collector main and arranged to be actuated for the purpose of throwing tar 100 into the stream of gases and upon the exposed surfaces of the main. Discs, plates or spines on rotating shafts will achieve the same purpose. The required agitation can also be accomplished by the introduction of 105 compressed gases such, for example, as fuel or coke-oven gases or steam through a suitable distributor pipe imersed in the tar or suction T's (McDaniel type ejectors) may be located in the main with their suction 110 ends beneath the level of the tar therein. If the nozzles of the ejectors are allowed to extend above the surface of the tar a spray of tar will be thrown into the gas. The effect of one or more of the mechanical agitating 115 devices mentioned may be augmented by the provision of suitable spray nozzles in the collector main and goose-neck through which tar may be sprayed into the stream of gases flowing through the main.

120 Although indiscriminate cooling of the gases in the collector main as heretofore practiced is to be avoided, it may be desirable to introduce water or ammonia liquor with the tar which is sprayed into the collector main to cool the gases to a predetermined and regulated extent. The regulation of the cooling effect can be accomplished more readily with water because of the higher specific and latent heats of water as compared with tar 125

and oils. It is possible, therefore, to add water or ammonia liquor in the proportion required to remove all heat except that needed for the distillation of the tar. When hard pitch is desired less water can be added, or no water at all. Cooling of the gases to a greater or less extent can be accomplished also by the addition thereto of cold gases, such as fuel gas, cooled coke-oven gas, etc. Instead of cooling, additional heat may be made available, where this is desired, by passing such gases over the incandescent surface of the coke in the ovens and thence through the uptakes to the collector main. The distilling capacity of the gases from a single coke oven battery is greatly in excess of that required for the distillation of the amount of tar which that single coke-oven battery produces so that the tar from a considerable number of coke-oven batteries can be distilled by the hot gases from a single battery. Consequently, to maintain the operation as hereinbefore described, it is ordinarily necessary to provide an amount of tar very much in excess of that produced by the single battery which is so operated or the volume of the gases used should be reduced to that which will distill the available tar, as, for example, by using such gases in a separate short collector main.

Where several coke-oven batteries are operated at a single plant, e. g., twenty batteries, the tar from several or all of the batteries can be distilled on a single battery by operation according to the present invention. Where there is only one or a few batteries the tar can be recovered in normal operation, e. g., with ammonia liquor sprayed in the collector main, and after a sufficient amount of tar has accumulated it may then be distilled in the collector main by operating one or more days in the manner described. If continuous operation with a relatively small amount of tar is desirable, the light or heavy oil from the condensers can be returned to the main in suitable proportion to the tar which is circulated. Such operation may be desirable when there is no provision for the accumulation of large stocks of tar.

Instead of carrying on the distillation in the collector main which is common to all of the ovens of the battery, a short collector main may be provided and connected to a few only of the ovens so as to receive the gases from those ovens while the gases from the remaining ovens pass through the large collector main. The ovens which are connected to the short collector main may also be connected with the large collector main and suitable valves may be employed to direct the gases through one or the other of the mains as may be desired. The short collector main may be suitably disposed either below or above or alongside of the large collector main or it may be placed at the opposite side of the battery. Instead of providing a long and a short collector main there may be a series of short collector mains, each connected to a number of the ovens of the battery so as to receive the gases from those ovens. In either arrangement the short collector mains may be provided with the mechanical agitating means to ensure the intimate contact of the tar or oil with the hot coke-oven gases flowing through the mains. The effect of mechanical agitation can be increased by the provision of tar sprays in the collector main and in the goose-necks leading thereto. Where separate short collector mains as hereinbefore described are provided, the gases leaving the short main or mains may be conveyed to separate condensing apparatus or into the collector or cross-over main or directly to the condensing apparatus which receives the gases from the large collector main. The condensing apparatus employed may be of the direct or indirect type and may be designed to permit fractional condensation of the condensable constituents in the gases.

The tar which is distilled according to the present invention may be tar produced at the same coke-oven plant or at another plant. The tar may be heavy tar, light tar or heavy or light tar constituents which it is desired to distill for the purpose of separating distillate oils therefrom. Other tar such as gas-house tar, vertical retort tar or water-gas tar, etc., can also be distilled, or light tar or tarry oils, etc. Where blended or composite pitches are desired or composite or blended distillates two or more different kinds of tar can be distilled separately at the coke-oven plant or they can be admixed in suitable proportions and can be distilled together, giving directly a composite pitch product. Where different tars are distilled the resulting pitches can be blended to give a composite product and the distillates can likewise be blended when desired. For example, horizontal gas-retort tar with high free carbon content can be admixed with coke-oven tar and the mixture can be distilled to give a composite pitch higher in free carbon than the pitch from the coke-oven tar and to give a composite oil distillate. The tar distilled may contain all or practically all of the condensable oils or it may be a heavy tar containing only part of the oils. Where mixed tars are distilled the condensates will be of a composite character. Where different tars are separately distilled the gases and vapors from such separate distillations can be condensed separately or together.

Tar as commonly produced and collected at coke-oven plants contains more or less water or ammonia liquor admixed therewith. Such tar can be employed directly and dehydrated as well as distilled or it can be partially or completely dehydrated before

subjecting it to distillation. The tar can also be preheated in any suitable manner to reduce it to a thinly fluid state which will facilitate the mechanical agitation of the tar and ensure intimate contact thereof with the hot coke-oven gases. The amount of heat contained in the hot coke-oven gases is, however, so great that effective dehydration as well as distillation can be accomplished readily and preheating the tar by separate preheating means will not usually be necessary.

In carrying out the process the tar may be brought into contact with the hot gases only once or it may be recirculated and brought again into contact with the hot gases to accomplish a further distillation and the production of harder pitches or even pitches of modified character such as those having increased free carbon content. This further distillation may take place by recirculating the tar or pitch through the same collector main or through another or other systems as, for example, successively through a series of short collector mains, so that distillates and pitches of the same or similar character are produced in different systems or distillates and pitches of different character in the different systems. By regulation of the agitation of the tar and by redistillation when necessary, it is possible to regulate the hardness of the pitches produced and to produce softer or harder pitches as desired. The further distillation of the pitch first produced to recover additional oil therefrom can be carried out in the collector main or in other distillation apparatus. By providing separate collector mains, each connected to a series of ovens, it is possible to produce distillates and pitches of different characteristics simultaneously and by operating separate condensing systems with such separate distillation systems condensed products having different properties can be produced simultaneously.

The present invention includes not only the distillation of tar for the production of distillate oils therefrom but also the production of pitches of varying properties and characteristics. By limiting the time of contact of the tar with hot gases and the temperature to which the tar is raised during distillation, pitches of low carbon content and oils of definite characteristics can be produced as hereinbefore described. When, however, the pitch first produced is recirculated, its temperature will be further raised and the temperature can be increased to such an extent that more or less decomposition will take place with resulting formation of the materials commonly known as free carbon, thus increasing the free carbon content of the pitch. It is thus possible by recirculation of the pitch and by regulating the agitation of the tar in the collector main so that the pitch is kept in contact with the hot

gases for a sufficient time to raise its temperature to the decomposition temperature to decompose or crack greater or less amount of the pitch and/or oil constituents and to produce a corresponding amount of free carbon in the product. 70

In addition to producing pitches of different properties and characteristics the present invention permits the production of distillates from tar or tar fractions or oils. Consequently it can be employed to distill a dirty oil or an oil contaminated with tar or pitch, to produce a cleaner distillate oil therefrom and a pitch residue. In systems where separate short collector mains are connected to 80 separate condensing systems, each system may be supplied with a different material, for example, one may distill tar in the manner described and another may distill a mixture of oils for the separation of the different oil constituents therefrom. 85

The gases escaping from the collector main operated in the manner hereinbefore described contain considerable quantities of vapors or oils derived from the distillation of the tar together with the usual fixed gases. The gases being still at a relatively high temperature in order that the oils may be retained in vapor form and thus separated from the pitch, may be subjected to any subsequent desirable treatment for the purpose of effecting the separation of the oil in fractions. Preferably the gases are withdrawn from the centre box of the collector main independently of the pitch circulating therein and are conducted through a cross-over main to the separation apparatus. If it is desired to cool the gases rapidly to a temperature necessary for the separation of one or more of the heavier of the volatile constituents, the gases may be sprayed in the cross-over main with ammonia liquor or oil or mixtures thereof and the resulting liquid can be conveyed to a decanter in order to separate the ammonia liquor from the condensed 100 tar or tarry oils. 105

Instead of cooling the gases and vapors rapidly they may be cooled progressively to effect a fractional condensation of the vapors to yield oil fractions of definite character. 115 The large increase in condensable vapor content of the gases due to the distillation of the tar thereby results in the recovery of a relatively greatly increased amount of light tar and oil products while the scrubbing and purifying effect of the tar on the gases gives relatively cleaner oil products than are normally obtained with ordinary by-product condensing systems. 120

The present invention is of more or less general application to the distillation of tar and oils and the recovery of distillates. The invention involves utilization of the hot coke-oven gases for the distillation of tar or oil by bringing the tar or oil into direct contact 125 130

therewith. The invention will be further illustrated by the following more detailed description which should be read with the accompanying drawings showing apparatus adapted for the practice of the invention, but it is intended and will be understood that the invention is not limited to specific details of the apparatus as illustrated in the drawings; in which

30 Fig. 8 is a plan view illustrating the application of multiple short collector mains to the battery; and

Fig. 9 shows a modified arrangement.

Referring to Figs. 1 and 2 of the drawings, 5 indicates a battery of coke ovens having individual uptake pipes and goose-necks 6 which connect the ovens with a collector main 7. The latter is designed to receive all of the gases from the individual coke ovens and to deliver them through a modified centre box 8 to a cross-over main 9 which is connected to 35 the condensing apparatus hereinafter described. The centre box is constructed and arranged so that a substantial depth of tar or pitch is maintained therein and in the collector main, as illustrated in Fig. 2a, and the 40 centre box is shown as larger than usual so it will hold a considerable body of tar or pitch. It may be provided with insulation (not shown).

50 The collector main is provided with a longitudinally extending shaft 10 having a plurality of paddles or arms 11 distributed throughout its length. The shaft is adapted to be driven through any suitable mechanical connection with a suitable source of power. 55 A pipe 12 is connected to the collector main, for example, at one end thereof and a pump 13 is provided to force tar or pitch from a receptacle 14 to the collector main. If desired, the tar or pitch may be distributed to the collector main at a plurality of points through suitable pipes provided for that purpose and it may be introduced, if desired, through spray nozzles 15 and 16 connected to such pipes in such a way as to permit the spraying 60 of the tar or pitch into the collector main.

The pitch which accumulates in the bottom of the collector main is withdrawn either continuously or intermittently through a pipe 17 and may be recirculated through a pump 18 and the pipes hereinbefore described or 70 the pitch can be withdrawn through a pipe 19 and delivered to a receptacle 20.

As hereinbefore described, the operation of the collector main involves the maintenance therein and the circulation therethrough of a sufficient quantity of tar or pitch to prevent the accumulation of hard pitch on the bottom and exposed surfaces thereof. The pitch is withdrawn continuously or intermittently through the outlet pipes and is either returned or is partly returned and partly replaced by tar or pitch from other sources. The effect of the agitator in the collector main is to throw the tar or pitch in a finely divided condition into the stream of gases 85 which pass therethrough and the tar or pitch is thus subjected by reason of its subdivision to intimate contact with the hot gases. This intimate contact effects a substantial distillation of the tar or pitch to produce a harder 90 pitch which, however, is carried along by the stream of tar and pitch in the bottom of the collector main and is prevented thus from accumulating and blocking the main. The tar or pitch is likewise thrown in finely divided condition onto the exposed surfaces of 95 the main and flushes its surfaces, therefore, and prevents accumulation of hard pitch thereon.

Because of the distilling effect of the hot coke-oven gases, these gases accumulate a considerable proportion of volatile oils which are distilled from the tar or pitch and these volatile oils remain in the gases at the temperature at which the collector main is operated, for example, a temperature of from 100° C. to 200° C. lower than that of the gases escaping from the coke ovens. The intimate contact between the gases and the tar or pitch in the collector main serves another important purpose in that it washes from the gases the more readily condensable tar constituents thereof, while still leaving a considerable proportion of the normal volatile constituents in the gases. It further washes 110 from the gases to a greater or less extent much of the entrained solid material such as free carbon, etc. The gases are thus not only enriched in the more volatile constituents but 115 are freed to some extent from insoluble and heavier entrained materials.

As hereinbefore indicated, the effect of the mechanical agitator in the collector main may be augmented by introducing all or a part 125 of the tar in the form of spray through spray nozzles provided for that purpose. These spray nozzles ensure the subdivision of the tar into minute particles and facilitate contact, therefore, between the hot coke-oven 130

gases and the tar particles with resulting improvement in the distilling effect.

The gases which escape from the centre box 8 to the cross-over main 9 carry therewith a large proportion of the volatile constituents of the tar which enters the collector main and are to a considerable degree freed not only from heavy tar constituents which are not volatile at the temperature of operation of the collector main but also from insoluble entrained matter. These gases may be subjected in the cross-over main to contact with ammonia liquor delivered thereto through a plurality of spray nozzles 21 supplied by a pipe 22 from any available source of ammonia liquor in the system. From the cross-over main the liquid containing any tar or oil constituents, together with the ammonia liquor, is delivered through a pipe 23 to a decanter 24 in which the ammonia liquor can be separated and returned, for example, through the receptacle 25, pump 26 and pipe 22 to the cross-over main. The tar or oil from the decanter is delivered through a pipe 27 to a receptacle 28. A pump 29 and pipe 30 permit delivery of tar or oil to the pipe 22 and the tar can be mixed with ammonia liquor employed as a cooling agent in the cross-over main. A pipe 31 connects the receptacle 24 with the tar receptacle. Tar from any other source can be delivered to the receptacle 14 through a pipe 14'.

The balance of the gases still containing oil constituents are delivered to condensers 32 wherein the available oil products are separated and from which they can be withdrawn to a decanter 33 for separation of ammonia liquor from the oil. The gases which escape from the condensers 32 are withdrawn through an exhauster 34 which ensures the movement of the gases through the system.

the mechanical agitating means in the collector main. In this case a plurality of vertical shafts 35 are disposed in the collector main 36, each shaft carrying a number of cones 37. The shafts are adapted to be actuated through any suitable source of power such as a small electric motor. When the shafts are rotated the cones which are immersed in the stream of tar in the bottom of the collector main throw the tar upwardly and in a finely divided form into the hot coke-oven gases which enter the collector main from the coke-oven battery 39. It is understood that the body of tar or pitch is maintained in the collector main as in the preceding embodiment of the invention.

In Fig. 5 of the drawings a shaft 40 extending longitudinally through the collector main 41 carries a plurality of discs 40'. The shaft 40 can be driven from any suitable source of power to cause the discs 40' to rotate in the body of tar or pitch in which they are immersed in the collector main. The rotation of the discs causes a spray of tar or pitch to be thrown into the stream of hot coke-oven gases which enter the collector main through uptake pipes 42 from the battery of coke ovens 43. This structure thus provides for the intimate mingling of the tar or pitch with the hot coke-oven gases to accomplish the distillation of the tar in the manner hereinbefore described. It is understood that the supply of tar or pitch in the collector main may be maintained as hereinbefore described. 85 90 95 100

Referring to Fig. 6 of the drawings a plurality of injectors 44 may be connected to a pipe 45 extending longitudinally through the collector main and adapted to be supplied with any suitable gas such as fuel gas, coke-oven gas, steam or the like, under pressure sufficient to produce an effective suction and injector action when the gas passes through the injectors. The suction side of the injectors may be immersed in the tar or pitch in the bottom of the collector main as shown and when gas under pressure is supplied in the manner described the tar or pitch will be directed upwardly in the form of a spray which will disperse throughout the entire space above the tar or pitch in the collector main 36, the tar or pitch being thus subjected to intimate contact with the coke-oven gases supplied through pipe 46 from the bottom of the collector main 36. The supply of tar or pitch may be discontinued, the collector main in the manner previously described. A brief description of the invention will now be given after a general collector main has been described. Thus, if 125

the usual uptake pipes and goose-necks 51 which communicate with the collector main 52 having a centre box 53 from which the gases and the condensate are delivered to a cross-over main 54 leading to the usual condenser system including the condensers 55. The gases are drawn through the system by an exhauster 56. The separated tar and ammonia liquor may be withdrawn through decanters (not shown) as in the usual practice. The structure so far as described is the ordinary arrangement and in the operation of this apparatus ammonia liquor in suitable quantity may be delivered to the collector main for the purpose of cooling the gases therein.

To permit the practice of the invention as herein described, a short collector main 57 may be disposed alongside of or above or in any suitable relation to the usual collector main, but is arranged preferably at the rear of the ovens and is connected to a plurality of such ovens by uptake pipes 58. Valves may be provided to permit direction of the 25 gases from the ovens into either of the collector mains. The short or auxiliary collector main is designed for the distillation of tar in the manner hereinbefore described and is provided, therefore, with an agitator as shown, for example, in Fig. 3. The agitator may be 30 of any of the forms hereinbefore described or their equivalents. The agitation of the tar or pitch results in throwing the latter in the form of a spray into the hot coke-oven gases delivered thereto from the uptake pipes, and the tar is consequently distilled. The tar and resulting pitch may be circulated as in the similar operation of the usual collector main. The tar or pitch can be withdrawn continuously or intermittently through a pipe 61 and returned by a pump 62 through a pipe 63 or it may be delivered through pipe 64' to a receptacle 64. Fresh tar or pitch can be introduced through a pipe 59.

The gases from the short or auxiliary collector main are withdrawn through a main 65 and delivered to condensers 66. These can be arranged in series and may be fractional condensers of either direct or indirect type to permit recovery of two or more different oil or tarry oil products from the gases leaving the short collector main. The condensates from the condensers are withdrawn and delivered to suitable receptacles. The remaining gases may then pass through a pipe 67 to the exhauster which maintains the proper balance of pressure in the system.

In Fig. 8 of the drawings I have illustrated another arrangement in which a plurality of short collector mains replace the usual collector main, each short collector main being connected to a plurality of uptake pipes so that the gases from a selected number of ovens can be utilized for the distillation of tar. This permits great flexibility in the capacity of the

plant for tar distillation since one or more of the short collector mains can be utilized for that purpose while the remaining collector mains are operated in the usual way.

Referring to the drawings, the coke-oven 70 battery 70 is provided with the usual uptake pipes and goose-necks 71 which communicate with a number of short collector mains 72, each having a centre box 73 from which the gases are delivered to a cross-over main 74 leading to the usual condenser system including the condensers 75. The gases are drawn through the system by an exhauster 76. The separated tar and ammonia liquor may be withdrawn through decanters as in the usual practice. The structure so far as described permits operation in the usual way.

The apparatus is designed, however, as hereinbefore indicated, to permit the distillation of tar in one or more of the short collector mains and for that purpose each may be provided with a suitable agitating device such as hereinbefore described, for example, a shaft with paddles thereon as shown in Fig. 3 and adapted to agitate the tar or pitch in the collector main and to throw it into the stream of hot coke oven gases passing through the main. Each collector main may be provided moreover with circulating line 80 and pump 82 to permit recirculation of tar or pitch through the main; together with inlet lines 84 for the introduction of such additional tar or pitch as may be necessary to permit the maintenance of the intended operation. Outlet lines 81 are provided by means of which regulated amounts of the tar or pitch can be drawn off or circulated into the next collector main, depending upon the regulation of the valves. The pipes 81 connecting the short collector main permit the pitch produced in one end to be pumped to the next main and from that main to the next in a continuous manner, while the tar or pitch can be recirculated to a greater or less extent through the individual mains. In this way, a progressive distillation of the tar and pitch can be effected with the taking off of progressively heavier vapors and the production of progressively heavier pitches. Part or all of the pitch produced in the individual collector mains may be drawn off as products of the distillation. If no tar is introduced except at the short collector main at one end of the battery, and if the tar is circulated and distilled in this main and the pitch then conveyed to the second main and there further circulated and distilled and the residue then to the third main and further circulated and distilled, the hardest pitch will be produced from the last main and the vapors driven off will be progressively heavier. The arrangement of Fig. 8 however, provides for operating the individual short main separately without discharging the tar or pitch from one main to

the other, and in that case products of the same or different properties may be produced in the different mains, depending upon the amount and character of the tar supplied and the extent to which it is circulated and distilled. The character of the operation in the different mains can be further modified by supplying additional tar or pitch to the individual mains through the pipe 84.

Each of the collector mains of Fig. 8 may be provided with a separate condensing system, for example, a series of condensers 83, designed to separate different oil fractions from the coke oven gases and vapors resulting from the distillation of the tar or pitch. It is to be understood that suitable valves will be included to permit the direction of the gases into the separate condensing system or into the primary condensing system for the battery as may be desired. By providing a series of separate condensing systems, it is possible to produce distillate oils of different properties from the admixed gases and vapors from the different short collector mains, particularly where these mains are operated in series or under different conditions so that pitches of different characteristics are produced in them and so that the vapors distilled off likewise vary in their characteristics. By regulating the distillation and condensation, it is possible to obtain directly by condensation a series of condensed products of differing properties and characteristics.

A modified arrangement is illustrated in Fig. 9 which shows the top of part of one side of a battery in elevation with three short collector mains 85 arranged at progressively different levels, each being connected with a series of four uptake pipes 88 and each having an individual centre box 86 and crossover main 87, each having agitators 89 therein for atomizing or spraying the tar or pitch into the gases passing through the main.

Individual supply pipes 90 are provided for each of the individual mains so that tar or pitch can be supplied to all of the mains if desired. Each main is also provided with circulating lines 91, 93 and 94 and circulating pump 92, and with a discharge line 95 for discharging the pitch residue from the main. The short mains are connected with overflow lines 96 by means of which the pitch can be permitted to overflow from one short main to the next main at a lower level and thence to the third main from which the pitch may likewise be permitted to overflow through the line 97. By means of the overflow pipes 96 and the valves therein, it is possible to permit a greater or less amount of the pitch to flow from one main to the next so that the pitch from one main can be, in whole or in part, discharged into the next, and the residue from the second into the first, etc., thus making possible the production and

withdrawal of different kinds of pitch from the separate short mains and also making possible the production of heavier distillates from the separate mains. Additional tar can be introduced into the respective short mains if desired, to modify the operation and the products produced, or all of the tar can be introduced into one main and the residue caused to flow progressively through the other mains. The individual condensing systems, such as are illustrated in Fig. 8 are not shown in Fig. 9.

The arrangement as described permits the operation of the coke oven in the usual manner and the utilization of a portion of the heat in the hot coke-oven gases for the purpose of distilling tar derived from the gases issuing from the other ovens of the battery or tar from other sources. As in the tar distillation in the usual collector main as previously described, it is essential to flush the short collector main or mains with a quantity of hot tar or pitch sufficient to prevent accumulation of hard pitch in the main or mains. The apparatus as described, including a short collector main or mains, is particularly useful where the quantity of tar to be distilled is relatively limited and insufficient to permit proper flushing of the usual large collector main. It can be utilized, therefore, at isolated coke-oven plants where a single battery of coke ovens is operated and where the quantity of tar obtainable from other sources is relatively limited. It permits the production of pitch having the desired characteristics and the recovery of valuable oils from the tar in a simple, effective and economical manner.

The advantages of the invention have been set forth in some detail and the preferred embodiments have been described. It is to be understood, however, that various changes may be made in the form and arrangements of the apparatus and in the operation as described without departing from the invention or sacrificing the advantages enumerated or any other advantageous results which may be accomplished by the application of the principles set forth.

In the accompanying claims I use the term tar to include not only raw tar but also the partly distilled tar or tarry oils which are introduced into the main and atomized or sprayed into the gases and distilled thereby.

I claim:—

1. The improvement in the operation of coal distillation plants with distillation of tar and production of pitch and oils therefrom and from the coal distillation gases, which comprises conveying the gases from a plurality of the ovens or retorts to a collector main above the surface of the tar while the gases contain substantially the same vapor content as when they left the ovens or retorts and are still at a temperature suffi-

ciently high to effect rapid distillation of tar and not greatly below that at which the gases leave the ovens or retorts, continuously introducing into the said main a quantity of
5 tar many times in excess of that contained in such gases and causing the tar to be distributed from the body thereof in the bottom of the main into the coal distillation gases in the form of spray which scrubs the gases and
10 washes the exposed walls of the main to prevent the carbonization of pitch thereon, whereby it is brought into intimate contact with such gases in a finely divided state to effect rapid distillation of the tar and to
15 scrub the gases so that the gases are considerably enriched in oil vapors and cleaned by the scrubbing treatment, continuously removing from the main the gases and vapors resulting from the distillation and cooling
20 the same to condense oils therefrom and withdrawing from the main the residue from the distillation.

2. The method of distilling tar and of producing pitches and distillate oils therefrom
25 and of simultaneously producing pitches and oils from coal distillation gases, which comprises conveying the gases from a plurality of coal distillation ovens or retorts, while at a sufficiently high temperature to effect rapid
30 distillation of tar, to a collector main, maintaining in the main a continually changing body of tar and pitch, introducing the gases into the main above the body of tar and pitch therein, continuously introducing into the
35 main the tar to be distilled in an amount several times that normally contained in the gases passing through the main, subjecting such body of tar and pitch to violent agitation to atomize or spray the same into the
40 gases and against the walls of the main above the body of tar therein to effect rapid distillation of the tar and simultaneous scrubbing and rapid cooling of the gases and washing of the exposed sides of the main, so as to
45 prevent the carbonization of pitch thereon, whereby pitch is scrubbed from the gases and combined with the body of tar and pitch at the same time that the tar is rapidly distilled and the resulting oil vapors are combined
50 with the gases passing through the main, passing the resulting gases and vapors to a condensing system to condense oils therefrom, and drawing off the resulting pitch from the main.

55 In testimony whereof I affix my signature.
STUART PARMELEE MILLER.
